[57] **CLAIM**

The ornamental design for a combined modular desk and multiple seat unit, substantially as shown.

DESCRIPTION

FIG. 1 is a perspective view of a combined modular desk and multiple seat unit showing my new design;
FIG. 2 is a side elevational view thereof;
FIG. 3 is a rear elevational view thereof;
FIG. 4 is a front elevational view thereof;
FIG. 5 is a top plan view thereof;
FIG. 6 is a bottom plan view thereof; and
FIG. 7 is a greatly enlarged fragmentary perspective of one of the pedestals of the modular desk.

FIG.1

FIG.2

FIG.3

FIG.4

FIG.5

FIG.6

FIG. 7
